UNITED STATES PATENT OFFICE.

JAMES H. W. SHAW, OF CALGARY, ALBERTA, CANADA, ASSIGNOR OF ONE-THIRD TO
ALFRED J. FELLOWS, OF ROCKPORT, WASHINGTON.

CONTAINER-CLOSURE REMOVER.

Application filed July 6, 1923. Serial No. 649,901.

To all whom it may concern:

Be it known that I, JAMES H. W. SHAW, a citizen of Canada, residing at Calgary, in the Province of Alberta, Dominion of Canada, have invented certain new and useful Improvements in Container-Closure Removers; and I do hereby declare the following to be a full, clear, and exact description of the invention, such as will enable others skilled in the art to which it appertains to make and use the same.

This invention relates to new and useful improvements in opening devices, and particularly to devices for removing the caps or closures of various types from receptacles.

One object of the invention is to provide a device of this character which is readily adaptable for use to remove the screw cap of a fruit jar, or the vacuum cap of a bottle or jar.

Another object is to provide a device of this character by means of which the rubber packing ring can be lifted from its contact with the shoulder of the jar, and the cap also lifted a sufficient distance to break the vacuum, and thereby permit the easy rotation of the cap.

Other objects and advantages will be apparent from the following description when taken in connection with the accompanying drawing.

In the drawing:

Figure 1 is a perspective view of the device.

Figure 2 is an inverted perspective view thereof.

Referring particularly to the accompanying drawing, 10 represents a substantially hexagonal plate forming the body of the remover, from two of the sides of which are extended the legs 11, said legs being disposed at right angles to the plane of the body and having their terminals bent to lie in a plane parallel with the body 10, and inwardly beneath the same, as shown at 12. These terminals are being rounded and formed with sharpened edges, for engagement beneath the rubber gasket of a fruit jar cap. The body of the plate is transversely slotted, as at 13, adjacent and parallel with another side, the portion between the slit, and the outer edge being offset downwardly, as shown at 14. The body is also slotted in parallel relation to the side opposite the last described side, as shown at 15, and the por-

tion between this slit and the edge of the body is offset downwardly, as shown at 16, to aline with the offset 14. Slidably disposed beneath the plate 10, and resting on the offset portions 14 and 16, is a flat bar 17, the end which projects from the cut off corner being bent at right angles to provide the third leg 18, having the terminal formed at 19, in a manner identical to that of the legs 11. The other end of the bar 17 is bent at right angles, but in the opposite direction to that of the leg 18, and is adapted for use in prying up the clamping bail of a jar cover, as shown at 17'.

In the body 10, adjacent one of the legs 11, is an opening 21, in which is received the offset lug 22 of the lever 23. The portion of the lever 23 which carries the offset lug 22 is formed with a curved edge face 24, which is arranged to engage with the upturned end 17', to cause the bar 17 to slide transversely of the plate, and thereby draw its inturned foot beneath the rubber gasket of the cap, and the corresponding ends of the legs 20 into engagement beneath other portions of the gasket. Thus a firm grip is obtained on the cap, and by imparting a rotat- 70
ing movement to the body 10, by means of the lever, the cap may be readily unscrewed from the jar. If desired, the lever may be 75 removed from the plate 10, when the end 17' is to be used for prying a clamping bail, as will be readily understood from the drawing.

What is claimed is:

1. A closure remover comprising a body having closure gripping legs, a member slid- 90
able on the body, a closure gripping leg on one end of the member and a projection on its other end, and means movably connected with the body and engageable with the said projection for moving the member and maintaining the leg of said member in gripping position.

2. A closure remover comprising a body having a pair of stationary closure gripping legs, a movable member on the body and having a leg and a terminal projecting out of the plane of the member, and a lever movably connected with the body and engageable with the terminal projection of the movable member for moving the leg into gripping position.

3. A closure remover comprising a body having stationary closure gripping legs, a 110

movable leg carried by the body for cooperative action with the gripping legs to grip a closure, one end of the movable leg being angularly turned, and a cam lever movably mounted on the body in position for engagement with the angularly turned end of the movable leg to move the latter into gripping position.

4. A closure remover including a body having angularly extending gripping legs on the peripheral edge of the body, a bar 10 slide transversely of the body and having

one end angularly extended for cooperation with the gripping legs to grip a closure, the other end of the bar being extended angularly in the opposite direction, and a lever movably connected with the body and engaged with the last-named end of the said bar. 15

In testimony whereof, I affix my signature, in the presence of two witnesses.

JAMES H. W. SHAW.
